UNITED STATES PATENT OFFICE.

WILLIAM B. ERB, OF CHICAGO, ILLINOIS.

PUMP.

1,136,946.

Specification of Letters Patent. Patented Apr. 27, 1915.

Application filed October 2, 1913. Serial No. 792,954.

To all whom it may concern:

Be it known that I, WILLIAM B. ERB, a citizen of the United States, residing at Chicago, in the county of Cook and State of Illinois, have invented new and useful Improvements in Pumps, of which the following is a specification, reference being had to the accompanying drawings, forming a part thereof.

10 The purpose of this invention is to provide an improved construction of pumps specially designed for deep wells, operable in others, by which the water is elevated by the use of compressed air both operating a 15 piston for positive lift of the water, and also acting upon the water by injection of the air thereto for inflating and elevating it.

It consists of the elements and features of construction shown and described, as indicated in the claims.

In the drawings:—Figure 1 is a vertical axial section of a well tube and pump apparatus connected therewith embodying this invention. Figs. 2, 3 and 4 are vertical sections on a larger scale than Fig. 1 of three vertically successive portions of the entire device. Fig. 5 is a section at the line, 5,—5, on Fig. 6. Fig. 6 is a section at the line, 6,—6, on Fig. 5. Fig. 7 is a section at the 30 line, 7,—7, on Fig. 4.

The well tube, 1, is presumed to be driven or sunken in the usual manner in the well bore into the water-bearing stratum. At its lower end it terminates in an inlet fitting, 2, 35 provided with a strainer, 3, below its inlet port, and a ball check valve, 4, above said port, the valve seat, 5, being screwed into an inlet port after the inspection of the ball valve there-through into a cage, 5^a, which 40 forms the upper part of said fitting and through which the water which passes the ball valve enters the well tube. The inlet fitting also supports the pump cylinder, 6, whose lower end is closed by the coupling 45 plug, 7, screwed into the cylinder, and onto the upper end of the inlet fitting.

8 is a rubber cushion let into the upper end of the coupling plug, 7, to serve as a buffer or yielding stop for the down stroke 50 of the piston. The well tube at its upper end is connected by a coupling, 10, with an up-lead pipe, 11, the cylinder, 6, being at its upper end fitted within the coupling, 10, so that the latter which is screwed into the upper 55 end of the well tube, 1, closes at the upper end the annular chamber, 12, which

is formed between the cylinder and the well tube. The piston, 14, as will be hereinafter more fully explained, is operated by compressed air admitted below it into the cylinder, lifting it to a pre-determined point as hereinafter explained, and the piston on its descent, however caused, is followed by the water entering from the chamber, 12, through ports, 15, at the upper end of the cylinder so that the cylinder above the piston is filled with water ready to be lifted upon the next upward stroke of the piston.

In pumps employing compressed air for operating the piston to elevate the water, as such pumps have been heretofore constructed, it has been customary to release the compressed air after each lifting stroke in order to vacate the cylinder for the return stroke of the piston. A specific purpose of this invention is to avoid wasting the compressed air, and to utilize for further up-lifting and discharge of the water the expansive force of the compressed air below the piston which remains after the piston has been thus lifted by the compressed air for positively lifting the water above it. For this purpose the cylinder, 6, is provided with a multiplicity of relatively small perforations, 16, at a level in the height of the cylinder which will be passed by the piston and exposed below its lower end by the time the piston's upper end reaches and laps slightly upon the ports, 15, leaving said ports still mainly uncovered, for communication between the water space, 12, and the cylinder chamber. When the parts, 16, are thus uncovered by the upward movement of the piston, the compressed air below the latter in the cylinder is discharged in a multiplicity of jets into the water in the chamber, 12, and thence through the ports, 15, into the cylinder and the up-lead pipe, 11, inflating and elevating the water and continuing and increasing its delivery upward to ultimate discharge.

At a distance above the highest position of the pump piston in the cylinder which will be desirably varied according to the different circumstances of each case, as, the depth of the well, the depth of submergence of the cylinder below the level of the water-bearing stratum and the degree of air pressure to be employed, there is located in the up-lead pipe a column-retaining check valve, 17. Since the piston stem must extend up within the up-lead pipe, the water passage

therein is necessarily annular, and the check valve and its seat are conformed to this circumstance. Inasmuch as the check valve is to be mounted variably as to its distance above the cylinder, the up-lead pipe is furnished at its lower part with a thin sleeve lining, 11^a, whose length covers the full range of probable variation of position of the check valve, and the check valve seat, 17^a, being secured into a bushing ring, 17^b, gripping an annular packing ring, 17^c, is fitted by means of said packing snugly within the said lining sleeve, 11^a, and is held fixedly suspended therein, in addition to its close fit in the sleeve, by means of a piston stem housing tube, 18, which is coupled at its lower end to the upper end of a sleeve-like hub, 17^d, with which the check valve seat is provided, and through which the piston stem extends, said housing being screwed at its upper end into a hollow boss, 19^a, which projects from the top wall of a water chamber, 19, which is mounted on the top of the up-lead pipe, and from which the final water discharge pipe 19^c, leads off. The check valve is seated by a spring, 17^f, coiled around the sleeve stem, 17^e, of said valve, said sleeve stem being mounted for sliding freely on the sleeve hub, 17^d, of the valve seat. The spring bears at its lower end upon the valve, 17, and is stopped at its upper end by the lower end of the coupling, 18^a. The pump piston stem, 20, passes loosely through the hub sleeve, 17^d, of the valve seat, the clearance around the stem being small so that the water passes only to a limited extent around the stem through the housing, 18. The boss, 19^a, is provided with vent apertures, 19^b, opening into the chamber, 19, at a point close to the top of said chamber. The primary purpose of these vent apertures is to permit the escape of air which may remain temporarily trapped below the check valve, 17, after the tension of the compressed air, originally operating, as above described, for lifting the water, has become reduced in such action so that it does not immediately find its way up through the water. This residue of air remaining in the passages below the check valve would diminish the capacity of the pump at each stroke thereafter, and it is important, therefore, that it should be allowed to escape, and this is effected through the space around the rod, 20, in the tubular connection of the check valve seat with the chamber, 19. In addition to this function, the ports, 19^b, serve to permit the easy upward movement and discharge from the space around the piston stem in the connecting pipe, 18, of the water, which may under some conditions of submersion be therein instead of the air above mentioned. This is desirable because the piston stem, 20, may have a coupling, 20^a, located in said pipe, 18, which would

operate more or less as a piston displacing the water in the movement of the piston in either direction, and thereby causing considerable resistance to the movement of the piston.

The compressed air is introduced into the cylinder through the piston stem, which is for that purpose hollow, and which for the same purpose extends up through the water chamber, 19, a stuffing box, 22, being provided on the upper side of said chamber through which the piston extends upward. Upon the upper side of said chamber, 19, there is mounted a housing, 23, for the upper end portion of the piston, the purpose of which is to afford means for giving the compressed air access to the cavity of the piston stem, and controlling entrance of the compressed air therethrough, as will hereinafter appear. For this purpose the pump piston stem at its upper end comprises a valve member, 24, and a cam member, 25, the two being in one piece which is hollow from its lower end upward to a point near its upper end, which is tapered, as shown, at 25, to form a cam for the purpose hereinafter explained; and in said tapered portion an aperture, 25^a, leads from the surface to the interior cavity of said member. Said valve-and-cam member is screwed at its lower end onto the upper end of the lower tubular portion of the pump piston stem, and immediately above the valve portion, 24, by which it is thus attached, it is cut away at opposite sides to form the lateral openings, 25^b, leading from its interior cavity into the chamber of the piston stem housing, 23. Onto the upper end of the piston-stem-housing, 23, there is bolted fast a member, 30, the lower end of said member and the upper end of the housing, 23, being provided with mated flanges for securing them together. The member, 30, is, or comprises substantially a continuation of the piston housing, but with a cavity of such diameter as to be fitted snugly piston-wise by the valve-and-cam-member, 24--25, of the pump piston stem; and said stem is extended upward, but without being hollow, in the rod portion, 26, and terminates in a second cam member, 27.

The member, 30, has mounted upon it at a position of its length intermediate the lower end in which the piston cam member, 25, is seated and the upper end portion in which the cam member, 27, is seated, oppositely transversely projecting valve chambers, 28, and 29, at a distance apart along the length of said member, 30; and upon said member, 30, at a point in its length intermediate said valve chambers, 28 and 29, there is mounted a balanced valve chamber, 31, which is cylindrical in form with its axis transverse to and its position lateral with respect to the piston housing member, 30. In this chamber there is a cylindrical bal-

anced valve, 34, which has a short range of reciprocation in said chamber, and has in each of its opposite heads a small port, 34^a, leading from the cavity of the valve into the cavity of the valve chamber. The valve chamber is furnished at its upper side with a compressed air inlet port, 31^a, at which is connected a compressed air supply pipe, 35, provided with a manually operable shut-off valve, 36. It will be understood that the pipe, 35, leads to a compressed air supply chamber not shown, the pipe, 35, being hereinafter referred to as the source of compressed air. The valve chamber, 31, has an exit port, 31^b, diametrically opposite the inlet port, 31^a, and the valve, 34, has corresponding inlet and exit ports, 34^b and 34^c, which register with the ports, 31^a and 31^b, respectively, when the valve, 34, is at one limit,—(the right hand in Fig. 5)—of its longitudinal movement in the chamber, 31. The valve, 34, is guided in said longitudinal movement and prevented from rotating in the chamber by a guide stud, 37, which projects from the upper side of the chamber wall into a slot, 34^d, of the valve which is, in fact, a continuation of the port, 34^b, and has the effect of causing the interior cavity of the valve to be at all times in communication with the inlet port, 31^a, leading from the compressed air source. The chamber, 31, is in communication at its opposite ends, respectively, with valve chambers, 28 and 29, said communication being effected by the passages, 28^a and 29^a, respectively, leading laterally from said balanced valve chamber and entering laterally into the valve chambers, 28 and 29, respectively, at the inner ends of said valve chambers, respectively. In said last mentioned valve chambers there are provided piston valves, 28^b, 29^b, which are normally held seated over the inlet ports, 28^a and 29^a, by springs, 28^c, 29^c. Said valve chambers open axially with respect to the bosses in which they are formed, radially into the cavity of the piston stem housing, 30, and said valves are provided respectively with stems, 28^d and 29^d, which fit the extension of said valve chambers into the cavity of said pump piston stem housing; said stems having axial bores from their inner ends terminating in said housing chamber back of the point at which the stems join the body of the valve, and said axial ports are there connected by laterally-leading ports, 28^e, 29^e, with the valve chambers, respectively; so that when the valves are pushed back in their chambers against the resistance of their respective springs, communication is opened between the chambers of said valves respectively and the cavity of the piston stem housing in the member, 30; and thence through the piston stem to the pump cylinder below the pump piston; and the valves, 28^b and 29^b, are by the same movement moved to uncover the ports, 28^a and 29^a, leading from the balanced valve chamber, 31, which is thus put in communication alternately at opposite ends with the pump cylinder below the piston. The cam members, 25 and 27, on the pump piston stem at the opposite extremities of the rod portion, 26, thereof, are adapted to encounter the ends of the hollow valve stems, 28^d and 29^d, in the opposite strokes of the piston so as to open said valves, 28^b and 29^b, alternately at opposite stages of the pump piston's movement.

The operation of the valve mechanism above described is as follows:—Assuming the piston, 14, to be at the bottom of its stroke in the cylinder, the cam member, 27, will be in a position at which having encountered the stem of the valve, 29^b, and thrust that valve open, it is holding the same in open position maintaining air communication between the cavity of the housing, 30, and the right hand end of the balanced valve chamber, 31. At this stage, the balanced valve, 34, is at the position shown in Fig. 5, opening communication from the source of compressed air into the passage, 39, leading from the lower side of the balanced valve chamber and thence horizontally in the lower side of the casting forming said chamber, to the face thereof by which it is mounted upon the member, 30, where said passage registers with a duct, 40, formed in the latter and leading to the lower end thereof where it opens into the cavity of the housing, 23. By this passage the compressed air is admitted through the ports, 25^e, into the axial cavity of the hollow piston stem, 20, and thereby into the cylinder, 6, below the piston. The several parts being at rest in this position, upon the operator opening the valve, 36, and admitting the compressed air, the piston will be forced upward in the cylinder, lifting the water above it in the cylinder, and in the up-lead pipe past the check valve, 17, and,—assuming the up-lead pipe and chamber, 19, and passage pipe, 20, to be already full of water,—the water will be by this movement discharged from the upper end of said discharge pipe. When in this movement the lower end of the piston passes and uncovers the ports, 16, the compressed air below the piston forcing its way past the check valve, 50, is discharged in a multiplicity of jets out through the ports, 16, out into the chamber, 12; and thence, passing around the piston back and through the ports, 15, inflating the water in the cylinder and up-lead pipe above the piston, and thereby uplifting the body of the water thereabove, it causes further discharge from the discharge pipe, 19^c. In the upward movement of the piston and about the time it passes and uncovers the ports, 16, 130

the lower end of the piston valve cam member, 25,—that is, the portion thereof below the ports, 25^c,—enters the housing member, 30, and, operating as a valve therein, shuts off the communication of the compressed air with the cavity of the hollow piston stem.

Substantially simultaneously with the cutting off of the compressed air communication with the piston stem, which is effected by means of the valve end, 24, as described, the upper cam end, 25, encounters the stem of the valve, 28^b, and thrusts the same inward, opening that valve. The supply of compressed air being cut off and the compressed air expanding by discharge into the water for inflating and lifting the same, as described, the tension of the air in the cylinder below the piston and in the cavity of the piston stem, will be reduced and the valve, 28^b, being open establishing communication for said air under reduced tension with the left hand end of the balanced valve chamber, 31, the tension of the air in that end of the chamber being reduced will unbalance the valve and cause it to be moved to the left, cutting off the communication which it controls with the compressed air source. The movements described of the balanced valve result because of the relatively small communication afforded by the port, 34^a, from the interior of the valve to the right hand end of the chamber, in comparison with the vent for escape of compressed air afforded by the passages 28^a and 29^a.

35. The compressed air in the cylinder below the piston continuing to expand and inflate, elevate and discharge the water from above the piston, the tension of said air will eventually be reduced so that it will no longer support the piston and its stem and its appurtenant members, and the piston will descend in the cylinder to the bottom thereof. In the last short increment of the descending movement of the pump piston, 40. the cam member, 27, at the upper end of the rod member, 26, of the piston stem encounters the stem of the valve, 29^b, and opens said valve, thereby effecting communication from the chamber of the housing, 30, to the right hand end of the balanced valve chamber, causing said valve to be again unbalanced, which will result in its movement in the opposite direction from that previously occurring, and its arrival at the position shown in Fig. 5 at which free communication is opened through it from the compressed air source to the cavity of the housing, 23. The piston continuing to descend, the valve member, 24, on the piston stem emerges from its seat in the housing, 30, and the ports, 25^c, are uncovered, admitting the compressed air to the cavity of the hollow stem, and thence into the cylinder below the piston, whereupon the cycle of movement above described will be repeated.

The pump piston is provided at its lower end with a check valve, 50, which controls ports, 51, in the lower end section of the piston through which the water is admitted to pass the check valve and enter the space, 14^b, between said lower section, 14^a, and the main body of the piston, 14. The purpose of this is to adapt the piston to pick up from the bottom of the cylinder any water which may have obtained entrance by leakage past the piston, or otherwise, so as to permit the piston at full stroke to descend to the bottom of the cylinder and thus obtain its full range of action upward. The water thus picked up and carried in the space, 14^b, will be ejected by the air, as above described, when the piston rises so as to bring the space, 14^b, opposite the perforations, 16.

I claim:—

1. In a pump, in combination with a pump piston and a cylinder in which it reciprocates, a by-pass from a lower to a higher point on the cylinder chamber around a certain position of the piston therein at the upper part of its stroke; a hollow piston stem opening into the cylinder below the piston; a source of compressed air and means for alternately admitting it to and excluding it from the piston stem, said means comprising a valve which is operated by the compressed air, and devices operated by the up-and-down movement of the piston stem for unbalancing the air pressure on said valve oppositely at opposite stages of the piston stem's movement.

2. In combination with a pump piston and a cylinder in which it reciprocates, a by-pass from a lower to a higher point of the cylinder chamber around a certain position of the piston therein at the upper part of its stroke; a source of compressed air; a passage leading from the piston chamber below the piston to said compressed air source; a device for controlling communication through said passage; a valve operated by the piston for controlling said passage at a point intermediate the first-mentioned controlling device and the pump cylinder; an auxiliary passage not controlled by the last-mentioned valve connecting the previously-mentioned passage with the first-mentioned controlling device, and valves operated by the piston at opposite stages of its stroke for controlling the communication of said auxiliary passage with said first-mentioned controlling device.

3. In combination with a pump piston and a pump cylinder in which it reciprocates, an up-lead pipe connected to the upper end and leading to a discharge; a check valve in the up-lead pipe opening discharge-ward; a by-pass from a lower to a higher point of the cylinder chamber around a cer-

tain position of the piston therein at the upper part of its stroke; a hollow piston stem opening into the cylinder below the piston; a source of compressed air and means for alternately admitting it to and releasing it from the piston stem, said means comprising a valve which is operated by the compressed air, and devices operated by the up-and-down movement of the piston stem for unbalancing the air pressure on said valve oppositely at opposite stages of the movement of the piston stem.

4. In combination with a well tube or casing, a pump cylinder supported within the casing and positioned therein to afford water space between it and the casing wall; a check valve at the foot of the casing admitting water to said water space; a piston mounted for reciprocation in the cylinder, the latter having communication with said water space near the upper limit of the piston's stroke in the cylinder, and also at its upper part below the piston's position at said limit, whereby a by-pass is formed around the piston at said position; a hollow piston stem opening into the pump cylinder below the piston; a source of compressed air and means for alternately admitting it to and releasing it from the piston stem, said means comprising a valve which is operated by the compressed air, and devices operated by the up-and-down movement of the piston stem for unbalancing the air pressure on said valve oppositely at the opposite stages of the piston's movement.

5. In combination with a pump piston and a pump cylinder in which it reciprocates, a by-pass from a lower to a higher point of the cylinder chamber around a certain position of the piston therein at the upper part of its stroke; a hollow piston stem opening into the cylinder below the piston; a source of compressed air and means for alternately admitting it to and releasing it from the piston stem; said means comprising a piston valve and its chamber provided with means for communicating with the source of compressed air adapted to admit balanced pressure to the valve, passages affording communication from the pump piston chamber below the piston to the piston valve chamber at opposite sides of the valve therein, and means by which the pump piston stem opens said communications alternately at opposite stages of its stroke.

6. In combination with a pump piston and a pump cylinder in which it reciprocates, a by-pass from a lower to a higher point of the pump cylinder around a certain position of the piston therein at the upper part of the stroke of the latter; a compressed-air-controlling device and a passage therefrom to the pump cylinder below the piston, said controlling device comprising a balanced

piston valve and its chamber, said chamber having two inlet ports at opposite sides of the piston valve; a valve device operating in the compressed-air passage which leads to the pump cylinder for cutting off communication between the same and the compressed-air-controlling device; air connections not controlled by said valve leading from said passage to said inlet ports; valves which control said connections respectively, and means by which the piston operates said valves alternately at opposite stages of its stroke.

7. In combination with a pump piston and a pump cylinder in which it reciprocates, an up-lead pipe leading from its upper end; a by-pass from a lower to a higher point of the cylinder chamber around a certain position of the piston therein at the upper part of its stroke; a hollow piston stem opening into the cylinder below the piston; a housing for the piston stem above the up-lead pipe and a fitting which closes communication of said housing with the up-lead pipe and constitutes a stuffing box for the stem; a piston valve member on the stem above the stuffing box; a seat for said piston valve in the housing; a compressed-air-controlling device and a passage therefrom leading into the piston-stem housing between said stuffing box and the piston valve seat, the piston stem having an opening leading from its cavity into the cavity of said housing for communication with said passage, said controlling device comprising a balanced piston valve and its chamber, the latter having ports for air communication at opposite sides of the piston valve therein; ducts from said ports to the piston housing above said piston valve member; valves controlling said ducts, the piston stem having means for operating said valves alternately at opposite stages of its stroke.

8. In combination with a well tube or casing, a pump cylinder supported within the casing and positioned therein to afford water space between it and the casing wall; a piston mounted for reciprocation in the cylinder, the latter having communication with said water space near the upper limit of the piston's stroke in the cylinder, and also at its upper part below the piston's position at said upper limit, whereby a by-pass for air is formed around the piston at said position, the last-mentioned of said communications being by means of a multiplicity of relatively small perforations for subdividing the air into small jets at its emergence into the water; a hollow piston stem opening into the pump cylinder below the piston; a source of compressed air and means for alternately admitting it to and releasing it from the piston stem.

9. In combination with a pump piston and a cylinder in which it reciprocates; a

- source of compressed air; a passage leading from the piston chamber below the piston to said compressed-air source; means for opening communication for the compressed air into the space above the piston at a pre-determined point in the upward movement of the piston; a device for controlling communication through the compressed-air passage leading to the piston chamber; a valve 5 operated by the piston for controlling said passage at a point intermediate the first-mentioned controlling device and the pump cylinder; an auxiliary passage not controlled by the last-mentioned valve connecting the 10 previously-mentioned passage with the first-mentioned controlling device, and valves operated by the piston at opposite stages of its stroke for controlling the communication of said auxiliary passage with the first-mentioned controlling device.
10. In a pump, in combination with a pump piston and a cylinder in which it reciprocates, an up-lead pipe from the upper end of the cylinder for water discharge; a 15 hollow piston stem opening into the cylinder below the piston; a source of compressed air and means for alternately admitting it to and excluding it from the piston stem; means for opening communication for the 20 compressed air from the piston stem into the up-lead pipe at a pre-determined point in the rising movement of the piston, and means for controlling the admission of compressed air to the piston stem comprising a 25 valve and two air connections for operating it in opposite directions, said air connections leading from the piston stem; valves which control said connections respectively, and means carried by the piston stem for operating said valves respectively at opposite 30 stages of the piston's movement.
11. In a pump, in combination with a pump piston and a cylinder in which it reciprocates, a well tube within which the 35 cylinder is positioned having access for water to the space around the cylinder, the cylinder having communication near its upper end with said water space for receiving water therefrom above the piston; means 40 for supplying and intermitting the supply of compressed air to the cylinder below the piston to cause reciprocation of the piston, the cylinder having ports for communication from its chamber with the water space around it in the well tube at a position to be uncovered by the upward movement of the piston near the upper limit of its stroke, for admitting the compressed air from below the piston into the water space around 45 the cylinder and thence back into the cylinder above the piston.
12. In a pump, in combination with a pump piston and a cylinder in which it reciprocates, a well tube within which the cylinder is positioned having access for water 50 to the space around the cylinder, the cylinder having communication near its upper end with said water space for receiving water therefrom above the piston; means for supplying and intermitting the supply of compressed air to the cylinder below the piston to cause reciprocation of the piston, the cylinder having ports for communication from its chamber with the water space around it in the well tube at a position to be uncovered by the upward movement of the piston near the upper limit of its stroke, for admitting the compressed air from below the piston into the water space around 55 the cylinder and thence back into the cylinder above the piston.
13. In combination with a pump piston and a cylinder in which it reciprocates, an up-lead pipe connected to the upper end of the cylinder; a water chamber at the upper end of the up-lead pipe; means by which the piston stem is extended water-tight through the top of said chamber; a housing 60 for the piston stem above said chamber; a conduit leading from a source of compressed air opening into the housing, the piston stem having an opening into its cavity for communicating with the housing cavity; a valve member on the piston stem, and a seat on the housing co-operating with said valve member for cutting off communication between the compressed air conduit and the piston stem cavity; means for opening communication from the space in the cylinder below the piston into the space above the piston at a pre-determined point in the upward movement of the piston, and means for controlling and intermitting the admission of compressed air to said conduit.
14. In a pump, in combination with a pump piston and a cylinder in which it reciprocates, a source of compressed air and means for alternately admitting it to and 65 excluding it from the cavity of the cylinder below the piston, said means comprising a balanced valve device; air connections leading from the cylinder below the piston to opposite sides of such valve for unbalancing the latter; valves controlling said communications, and cams on the piston stem for operating said valves alternately at opposite stages of the piston's movement.
15. In a pump, in combination with a cylinder and piston therein and means for discharging compressed air into the up-take water passage above the piston, a check valve in said up-take passage; a housing which supports the check valve seat extend-

ing to the top of said up-take pipe, the piston stem extending loosely through said housing and the housing having vent apertures at its upper end above the up-take pipe.

- 5 16. In a pump, in combination with the pump piston, a cylinder in which it reciprocates; a source of compressed air; a conduit therefrom to the cavity of the cylinder
10 below the piston; means for opening communication from said cavity into the space above the piston at a pre-determined point in the upward movement of the piston; a balanced valve device for alternately admitting and excluding compressed air from

said conduit; means for operating said balanced valve comprising air connections from the space in the cylinder below the piston to opposite sides of the balanced valve; valves which control said connections, and 20 means operated by the piston's movement for opening said valves alternately at opposite stages of the piston's movement.

In testimony whereof, I have hereunto set my hand at Chicago, Illinois, this 29th 25 day of September, 1913.

WILLIAM B. ERB.
